Primary Examiner — Mary Ann Calabrese(74) *Attorney, Agent, or Firm* — Workman Nydegger(57) **CLAIM**

The ornamental design for a desk, as shown and described.

DESCRIPTION

FIG. 1 is a front perspective view of a desk;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The lines consisting of uniform dashes shown in the drawings illustrate portions of the desk that form no part of the claimed design. The lines consisting of alternating long and short dashes define the bounds of the claimed design and form no part thereof.
